GUIDE CONTROL MEANS FOR WEB MATERIAL

Paul E. Friedemann, Wilkinsburg, Pa., assignor
to Westinghouse Electric & Manufacturing
Company, East Pittsburgh, Pa., a corporation
of Pennsylvania

Application August 24, 1934, Serial No. 741,266

17 Claims. (Cl. 271—2.6)

My invention relates generally to the control of traveling webs to maintain them in a desired operating position.

More particularly my invention relates to control means for controlling the transverse movements, or position, of a strip of material with reference to certain elements of a machine moving the material in a certain general direction.

My invention is an improvement on the equipment disclosed and claimed in the joint application of Finn H. Gulliksen and Stephen A. Staeg, filed January 14, 1933, Serial No. 651,722, and relating to Wire guide control.

In the art of paper making, mechanical means are provided to maintain the Fourdrinier wire in a given position on the guide roll or rolls, but such devices require considerable actuating force from the wire with the result that the wire becomes frayed at the edges. Serious breakage may thus result, and what is equally as detrimental, the useful life of the wire is very materially shortened.

By the control apparatus I herein describe and claim in the claims hereto appended, the edge of the web, whether such web be a Fourdrinier wire, a single wire, a felt, a strip of paper in a printing press, drive belt, conveyor belt, or any other web, is not subject to wear.

It is an object of my invention to provide electric control means whereby the travel of a web in a machine may be kept in a substantially definite or predetermined path.

Another and somewhat more specific object of my invention is to provide a system of control for a machine moving a web of material in a certain general direction which system of control includes two groups of elements cooperating with the web and cooperating with each other to restrict the lateral movement of the web of material to a certain path of travel when all the elements of both groups are in operative condition and which restricts the cooperative action of the web and control system to one group of elements when any one, several, or all of certain elements of the other group of elements fail to thus nevertheless restrict the movements of the web within the desired path of travel.

Another object of my invention is the provision of electric control means whereby a web of material may be made to follow a given path even though a portion of the control means may have become inoperative.

A more specific object of my invention is to provide two groups of cooperating control elements, cooperatively related with a web of material mov-

ing in a certain general direction, adapted to restrict the lateral meanderings of the web of material within certain limits, said control elements being designed to have their circuit arrangements changed by the failure of any one, several, or all, of certain elements in one or the other group of elements so that the web cooperates only with the group of elements in operative condition and is thus nevertheless restricted to substantially the same path of travel, namely, its meanderings are restricted to substantially the same limits despite the failure of certain elements in a group of the control elements.

Other objects and advantages of my invention will become more apparent from a study of the specification and the claims appended thereto when considered in conjunction with the accompanying drawings, in which:

Figure 1 is a diagrammatic showing of a photoelectric system of control for maintaining a web of material in a given path;

Figs. 2 and 3 are diagrammatic showings of modifications of my invention shown in Fig. 1; and

Fig 4 is a diagrammatic showing of a modification of my invention utilizing a mechanically operable switching means to rearrange the circuits of my control system to accomplish the novel results of my invention.

Referring more particularly to Fig. 1, where a system of control is shown for controlling the lateral movements of a web, reference numeral 1 designates a guide roll which is but one, preferably the end roll, of a plurality of rolls, and which guide roll may be shifted in angular position about the pivot point 2 by a bearing shifting means 3 shown at the left of the roll 1 and operated by the reversible motor 4. The axis of the roll will thus take various angular positions with reference to a given average position substantially parallel to the axes of other rollers, such as 5. The shifting of the roll 1 will positively produce lateral or transverse movements of the web 6 during the travel of the web 6 which travel is produced by a main motor M, suitably controlled by a controller C. That is, normally the rolls as represented by 5 are driven to move the web in a general direction as indicated by the arrow on the web, but the bearing shifting means 3 for the roll 1 will cause a positive transverse movement of the web and the direction of such transverse movement will depend upon the direction of movement of the bearing 1 at the left of roll 1.

In normal operation for printing presses, wind-

ing machines, and particularly in the art of paper making, the web of material, which, in the art of making paper, is usually a Fourdrinier wire, for some cause has the normal and usual habit of 5 meandering, that is, of moving from the right to the left and the left to the right thus shifting its path of travel. This shifting of the path of travel has no natural limits, so that the web of material will run off the rolls and will be damaged 10 or broken in the absence of some control means for restricting the lateral or transverse movements of the web. Meandering of the web of material within certain limits is, of course, permissible provided the limits set are within safe or 15 desired operations.

The rolls 1 and 5 may represent a pair of idler rolls, constituting parts of a paper making machine whereas certain other rolls not shown may be adapted to drive the web in the general direction indicated by the arrow on the web 6. However, as shown, a suitable main motor M is provided for driving the machine for operating the web, and this motor has suitable starting control means C, but since neither the motor M, nor 20 the control system of the main motor M in any wise in themselves constitute a part of this invention, none of these elements are shown in detail.

My invention as herein disclosed is adapted to 30 a control system for shifting the bearing 7 of the roll 1 by suitable operation of the bearing shifting means 3 through the reversible motor 4. To control the reversible motor 4 as a function of the lateral position of the web 6 I provide a pair 35 of directional contactors 8 and 9 adapted to interconnect the motor 4 with a source of direct current designated by the buses 10 and 11, when the web has meandered from its desired path of travel an amount sufficient to intercept the light 40 emitted from the sources of light 12 and 13 normally falling on the photocells or photo-tubes 14 and 15. The light will, of course, be intercepted either for the light 12 or the light 13, since these lights as well as the photocells are spaced equal 45 distances from the mid-line of the desired path of travel so that the web 6 has a permissible lateral movement determined by the distance of the edges of the web from the rays of light passing from the sources of light to the respective photo- 50 tocells.

The photocells 14 and 15 as well as the lights 12 and 13 and a pair of control relays 24 and 25 are interconnected with a pair of buses 16 and 17 energized with alternating current. The photocells 55 14 and 15 are indirectly connected to buses 16 and 17 whereas the lights 12 and 13 are connected directly across the buses 16 and 17. Whether or not these portions of the control circuit are connected exactly as specified is not 60 important. It is sufficient to say that they are energized in a desired manner. The photocells 14 and 15 are interconnected with a pair of electric discharge devices 20 and 21 and the actuating coils 22 and 23 of control relays 24 and 25. 65 The interconnection of the electric discharge devices with the photocells is such that the output current namely the current in the actuating coils 22 and 23 of the control relays 24 and 25, respectively, is a function of the quantity of light falling 70 on the phototubes 14 and 15. In other words, when the web 6 intercepts the light falling on these photo-tubes, the current in the actuating coils 22 and 23 will be reduced so that these control relays 24 and 25 become deenergized.

75 The control relays 24 and 25 being normally en-

ergized will set up circuits when deenergized to start the reversing motor 4 in such a direction as to re-position the web 6 on the rolls 1 and 5 so that the particular phototube that may have been darkened by the web will again be subjected to 5 the light of the source of light associated with the photocell. For instance, if the web 6 intercepts the light from the source of light 12 so that the illumination on photocell 14 is decreased the current in the actuating coil 22 is decreased, and 10 in consequence the directional contactor 8 is energized, causing the operation of the reversible motor 4 in such a direction that the bearing 7 is shifted to thus positively cause the movement 15 of the web 6 toward the right. On the other hand, if the light falling on photo-tube 15 from the source of light 13 is intercepted by the web 6, the actuating coil 23 will be deenergized, setting up circuits for the directional contactor 8 to thus cause the motor 4 to operate to shift 20 the bearing 7 in such a direction that the web 6 is positively shifted toward the left.

From the foregoing general statements, it is apparent that the web 6 may meander within 25 certain limits, but as soon as one or the other of the photocells is darkened, circuits are established for operating the motor 4 to re-position the web to such a position that the light is no longer intercepted. Thereafter the web is free to have a 30 transverse movement, the limits of which are determined by the positioning of the photocells 14 and 15 and lights 12 and 13 respectively cooperating with these photocells. If, however, a photocell, or a source of light, or an electric discharge device or two of these units or all three of these 35 units should fail, it becomes clear that the particular edge of the web at which the failure of any one, several, or all of these units mentioned takes place, can no longer operate to properly control the motor 4 to maintain the web in the 40 desired path of travel.

To increase the reliability, the safety, and efficiency of my system of control, and to eliminate the need for additional safety devices, I make provision for changing the control, should a failure of any one, several, or all of the units mentioned take place at one or the other side or edge of the web, to that side or edge where no failure or failures occurred. The change or transfer is effected by the cooperative action of the control 45 relays 24 and 25, the contactor 26, and the master relay 27.

A better understanding of the novel features of my invention can probably be had from a study 55 of typical operations and cycles of operation for various actions or transverse movements of the web 6. In the circuit diagram shown in Fig. 1, switches 28 and 29 are shown as having been closed to energize the buses 16 and 17. Energizing circuits are thus established for the lights 12 and 13, and the transformers 18 and 19. From the secondaries of the transformers both the photocells 14 and 15, the two electric discharge devices 20 and 21 and the two actuating coils 22 and 23 of the control relays 24 and 25 are energized provided, of course, the web is in such a position that the light passing from the sources of light to the 60 respective photocells is not intercepted.

In Fig. 1, the web is shown as in the desired 70 position, so that an energizing circuit is established from the left terminal of the secondary of transformer 18 through the actuating coil 22 of control relay 24, resistor 30, cathode 31 of the electric discharge device 20, past the control grid 32 to anode 33, and back to the right terminal of 75

the secondary of transformer 18. The capacitor 34 has one junction connected intermediate the resistor 30 and the cathode 31 and the other junction connected intermediate the control grid 32 and the cathode 35 of the photo-tube 14. The anode 36 of the photo-tube is connected directly to the right terminal of the secondary of the transformer 18. The circuit arrangement just explained for the electric discharge device, the 10 capacitor and the phototube is known as a forward circuit, wherein the effective resistance of the photocell 14 and the amplifier tube or electric discharge device 20 in the output circuit, namely the circuit including the actuating coil 22 is a function of the illumination of the photocell 14.

A similar circuit is established for the actuating coil 23 of the control relay 25 which circuit may be traced from the right terminal of the transformer 19 of the secondary through the actuating coil 23, resistor 37, cathode 38, past the grid 39 to the anode 40 to the left terminal of the secondary of the transformer 19. The capacitor 41 has one junction connected intermediate the resistor 37 and the cathode 38 and the other junction connected intermediate the control grid 39 and the cathode 42 of the photocell 15. The anode 43 of the photocell 15 is connected directly to the left terminal of the secondary of the transformer 19. The actuating coil 23 of the control relay 25 is thus energized, and all of the contact members controlled by the control relay are in their actuated positions, some of them being opened and others being closed. For the energization of the actuating coil 22 heretofore explained the control relay 24 caused certain of its contact members to be open and certain other of its contact members to be closed.

If the attendant wishes to start the control of the moving web 6 by the cooperative action of the web with the lights, the photocells and the electric discharge devices, which, in turn, control the control relays, he will actuate the starting push button 44 to close the stop switch 45 whereupon a circuit is established from the positively energized bus 10 through the contact members 45 of the stop switch also controlled by the stop button 46 mechanically coupled to the starting push button 44, back contact members 47 of the time limit relay 48, actuating coil 49 of the line contactor 50 to the negatively energized bus 11. Operation of the line contactor 50 closes the contact members 51 and certain line contact members in controller C. Closing of the contact members 51 merely establishes circuits for motor 4 when the respective directional contactors 8 and 9 are suitably energized should the web 6 darken one or the other of the photocells 14 and 15.

The closing of the contact members, which are really part of controller C, may provide for the starting of the main motor M operating the machine to move the web in the general direction indicated. However, such is not at all necessary, but contact members controlled by coil 49 merely deenergize certain control circuits for the main motor, thereby stopping the entire machine, should power fail on the buses 16 and 17, or should any two of the electric units, namely the lights, photocells or the electric discharge devices, disposed on opposite sides of the web fail. Since neither the controller C nor the main motor M constitute parts of this invention, I believe it sufficient to schematically show these features.

After the operation of the line contactor 50, the two control relays 24 and 25, the directional contactors 8 and 9, the time limit relay 48, the con-

tactor 26 and the master relay 27 will all remain in the positions indicated as long as the web moves along its desired path of travel, namely the path indicated by the arrow on the web 6.

Since the web 6 has the natural habit of meandering unlimitedly, it will naturally, sooner or later, intercept the light falling on one or the other of the photocells and establish an operating circuit for the reversible motor 4 to readjust the position of the bearing 7 for the roll 1. Assuming that the web 6 meanders toward the left so that the light falling on the photocell 14 is intercepted, whereupon the bias on the grid 32 is changed so that the current in the actuating coil 22 is decreased by an amount sufficient to release the 15 armature of the control relay 24. As soon as the armature of the control relay is released, contact members 53, 54 and 55 close and contact members 56 open. The closing of the contact members 53 establishes an energizing circuit for the upper 20 coil 57 of the master relay 27 which thereupon closes its upper contact members 58. The closure of the upper contact members 58 can, however, establish no useful energized circuit at this time, since contact members 59 of the contactor 26 in 25 series with contact members 58 are still open. The closure of the contact members 54 can also not establish any useful energized circuit at this time, since the contact members 60 of the control relay 25 in series with contact members 54 are 30 still open.

The closure of the contact members 55, however, establishes a circuit from the energized bus 10 through the contact members 55 of control relay 24, contact members 61 of control relay 25, 35 the magnetizing coil 62 of the directional contactor 9 and conductor 63 to the energized bus 11. The main or magnetizing coil 62 of the directional contactor 9 being thus energized, the contact members 64 are closed whereupon a circuit is 40 established from the energized bus 10 through resistor 65, the armature 66 of the reversing motor 4, field winding 67, conductor 68 and contact members 64 and 51 to the energized bus 11. The motor 4 is thus caused to operate to shift the 45 bearing 7 in such a direction that the web 6 is positively caused to move toward the right. The shifting of the bearing 7 is continued until the web 6 is moved an amount sufficient to again permit the light from the source 12 to fall on the 50 photocell 14, whereupon the actuating coil 22 is again energized, the contact members 55 are opened, the magnetizing coil 62 is deenergized, and a short time thereafter the circuit for the motor 4 is opened at the contact members 64. 55 No further shifting of the bearing thus takes place and the web is again free to move transversely in whatever direction it pleases. The positive shifting of the web toward the right is only far enough to again position it in substantially 60 the average desired path of travel, the path indicated by the arrow. If the web 6 again moves toward the left, the cycle just explained is repeated and the web is again caused to positively move toward the right. 65

In order that there may be no hunting and also that the motor 4 may not be operated too frequently for short intervals of time, the directional contactor 9 is of the time limit type. To provide for the necessary time constant, a neutralizing coil 69 is connected directly across the buses 10 and 11 through a resistor 70. This neutralizing coil has but few ampere turns and is connected to act in opposition to the main magnetizing coil 62. Furthermore, the directional 75

5 contactor 8 is provided with a copper ring 11 inductively related to both the main or magnetizing coil 62 and the neutralizing coil 69, so that the armature 72 of the directional contactor 8 is returned in its non-actuated or open position a short interval of time after the opening of the contact members 55 by the reillumination of the photocell 14.

10 By reason of the time constant of the directional contactor 8, motor 4 will of course operate for a short time after the light again falls on the photocell 14, so that the web may be shifted some small distance away from the pencil of rays that passes from the source of light 12 to the 15 photocell 14.

15 If the time constant of the directional contactor 8 is such that the bearing 7 is moved more than was absolutely necessary, the web 6 will, of course, travel toward the right. If the web 6 travels 20 towards the right, the light falling on the photocell 15 may be intercepted, that is, the photocell 15 is darkened whereupon the energizing coil 23 is deenergized. It should be noted at this point, though, that an over-correction, that is, a time 25 constant of the directional contactor 8 which would normally cause the motor 4 to shift the bearing to such a position that the web would tend to move toward the right would not necessarily insure that the web would move towards the 30 right. The unequal distribution of the paper pulp on the Fourdrinier wire may provide a greater tension at one edge of the web than at another, so that in spite of one operation of the directional contactor 8 the web may again move 35 toward the left, in which case the cycle of operation above explained is repeated and the directional contactor 8 will be caused to operate a second and possibly even a third time. Sooner or later, however, the bearing 7 will be shifted by 40 an amount sufficient that the web will, in fact, move toward the right.

45 If the beam of light falling on the photocell 15 is intercepted by the web 6, the actuating coil 23 of the control relay 25 is deenergized with the result that the contact members 73, 60 and 74 are closed, and the contact members 61 are opened. When the web 6 moved away from the photocell 14, the contact members 53 were, of course, caused to be opened and in consequence the balanced master relay 27 moved to the position shown in Fig. 1 thereby opening the contact members 58. The closing of the contact members 73, therefore, causes the energization of the lower actuating coil 75 of the master relay 27, 50 whereupon the contact members 76 are closed. Closing of the contact members 76 does, however, not establish any useful energizing circuit at this time, since the contact members 59 of the contactor 26 in series with contact members 76 are 55 open. The closing of the contact members 60 also does not establish any useful energizing circuit at this time, since the actuating coil 22 will be energized when the web is at the right, thus the contact members 54 will be opened.

60 The closure of the contact members 74, however, establishes a circuit from the energized bus 10 through the contact members 56 and 74 to the main or magnetizing coil 78 of the directional contactor 8 to the bus 11. The energization of the main or magnetizing coil 78 causes the closing of the contact members 79 whereupon a circuit is established from the energized bus 10 through the resistor 65, armature 66, field winding 80 and contact members 79 and 51 to the energized bus 11. The motor 4, being thus energized,

5 operates in such a direction that the bearing 7 is shifted in such a direction to positively cause the movement of the web 6 towards the left. The shifting of the bearing 7 will continue until light again falls on the photocell 15 and thereafter will continue for an interval of time determined by the time constant of the directional contactor 8.

10 The directional contactor 8 is similar in design in every respect to the directional contactor 9. The directional contactor 8 is thus provided with a neutralizing coil 81 connected across the buses 10 and 11 through the resistor 83 and a copper ring inductively related to both the magnetizing coil 78 and a neutralizing coil 81 aids in giving 15 the directional contactor its time constant. However, both the directional contactors 8 and 9 are provided with spring assemblies 84 and 85, respectively, for accurately adjusting the time constants 20 of these respective directional contactors.

25 As explained, the bearings 7 will be shifted so as to positively cause the web 6 to move toward the left. If the correction is more than sufficient the web will move toward the left and the motor 4 will be energized from the controlling action 30 of the photocell 14 in the manner previously explained. If the correction is not quite sufficient or if the loading characteristics of the web are such that the web nevertheless moves toward the right the cycle of operation just explained is 35 repeated until the web eventually moves toward the left.

40 From the discussion of the controlling action hereinbefore given, namely for the cycle of operation when the web is at the left as well as for the cycle of operation when the web is at the right, it should be apparent that in each instance when the bearing is shifted to positively drive the web away from the darkened photocell, the web again becomes absolutely free to meander in 45 whatever direction it pleases and may meander back to its first position or may meander toward the opposite side. In any case, the desired path of travel for the web is maintained regardless of whether it receives its controlling action from the 50 units, namely, photocell, light, and the electric discharge device on one side, or the units, the photocell, light and electric discharge device on the other side.

55 As long as all the mentioned units in the control system remain operative, there is no danger of causing the web to move off the rolls 1 and 5. However, if a light should fail, or a photo-tube fail, or an electric discharge device fail, it is clear that no controlling action can be expected from 60 that particular side at which any failure took place. Furthermore, with devices heretofore devised, if such failure took place, the web was driven off positively at one side of the rolls. In all of the devices of the prior art, this danger was 65 minimized by additional independent safety devices and no provision was made to make the control equipment absolutely reliable. Paper mill operators and certain engineers recognizing that there is danger from failure of any one of the 70 units mentioned, in consequence used photo-electrical control means only in addition to mechanical control means which would contact with the edges of the web should a failure of an electrical discharge device, a photocell or a light take place.

75 With my invention, such duplication of equipment to provide for safe operation is not necessary. My system of control, therefore, departs radically from other systems of control by making the equipment absolutely reliable as long as

there be no total failure of power, or as long as no two of the electric units, light, photocell and electric discharge device, on opposite sides of the web, fail at the same time. It should be readily apparent how remote the possibility is of having two electric units fail at the same time on opposite sides of the web, particularly when I provide indicating means to indicate when any one of the units fails.

10 My system of control thus satisfies a real need because everyone who has had to deal with electric lights, photocells or electric discharge devices, knows that these devices do occasionally "burn out" or fail. The trade generally must have recognized that the photo-electric control systems heretofore devised were not sufficient, since they were always used in conjunction with auxiliary mechanical safety devices.

To clearly understand the novel features generally explained, it should be noted that if an electric discharge device, a photocell, or a light fails, the particular actuating coil associated with the unit or units that failed will become deenergized. Assuming that either the light 12, the 20 photo-tube 14 or the discharge device 20 have failed, which, of course, means that no controlling action can be expected from the cooperative action of the left edge of the web with the units at the left edge. Such being the case, the actuating coil 22 is deenergized and in consequence contact members 53, 54 and 55 close, and the contact members 56 open. If, at the instant of failure the web be in the position shown, and the motor 4 not energized, then the closure of the contact 30 members 55 will establish a circuit for the directional contactor 8 in exactly the same manner as if the web 6 had intercepted the light falling on photocell 14. In consequence the web will be caused to move towards the right. Since, however, the actuating coil 22 remains deenergized, even though the web 6 may move towards the right sufficiently to intercept the light falling on the photocell 15, provision is made to nevertheless maintain the web 5 in the desired path of travel.

The closing of the contact members 53 causes the energization of the upper coil 57 of the master relay 27 which thereupon closes the contact members 58. When the web has moved toward the 50 right and intercepts the light falling on the photocell 15, the actuating coil 23 is deenergized with the result that the contact members 74 are closed, which would normally establish the energizing circuit for the directional contactor 8, should no trouble have developed at the left side of the web. Since, however, some one of the three units at the left failed, the contact members 56 are open and in consequence the directional contactor 8 is not energized through the contact members 74. The closure of the contact members 60 of the 60 control relay 25, however, establishes a circuit from the energized bus 10 through the actuating coil 86 of the contactor 26 and contact members 54 and 60 to the energized bus 11. Operation of the contactor 26 closes the contact members 59, whereupon a circuit is established from the energized bus 10 through contact members 59 and 58 and the main magnetizing coil 78 of the directional contactor 8 to the energized bus 11. The 70 motor 4 will thus be energized through the operation of the directional contactor 8 and will operate in such a direction as to positively shift the web toward the left and the operation of the motor will continue for a definite interval of 75 time, depending upon the time constant of the

directional contactor 8, after the light from the source of light 13 is no longer intercepted by the web 6 and thus falls freely on the photo-tube 15. In other words, the operation of the motor 4 continues even though the contact members 60 are opened to deenergize the actuating coil 86 of the contactor 26. Since the actuating coil 86 is deenergized, the circuit for the main magnetizing coil 78 will be opened at the contact members 59, but, by reason of the time constant of the directional contactor 8, the contact members 79 will remain closed for a short interval of time.

The deenergization of the actuating coil 23, of course, closes the contact members 13, but since the failure of one of the units at the left caused the previous closing of the contact members 53, the master relay 27 will have its armature in its upper position, namely the contact members 58 will be closed. The energization of the lower coil 75 of the master relay 27 will therefore have no effect on the movement of the armature of the master relay 27. This is a well known operation of any relay, because a considerably smaller current is needed to maintain the armature of a relay in engagement with the core of its magnetic circuit than is required to actuate the armature when the magnetic flux has to act through an air gap. Since the armature of the master relay 27 previously moved upwardly, the air gap is still greater than it normally is when the armature is held in its balanced position by the springs 88 and 89. There is thus no danger for the master relay 27 to make the wrong connection when the web has moved toward the right to intercept the light falling on the photocell 15.

The energization of the actuating coil 23 closes the contact members 61 to energize the main or magnetizing coil 62 of the directional contactor 9 to cause the closing of the contact members 64 in the absence of any mechanical interlock for the directional contactors. In practice, depending upon the size of the equipment, no mechanical interlock between the directional contactors is often needed, because the time interval during which both the contact members 64 and 79 are closed is comparatively short so that the reversible motor 4 would not tend to run away by the simultaneous energization of the fields 67 and 80 connected in opposition. This motor will be prevented from running away because soon after the closing of the contact members 64 the contact members 79 open and the reversible motor 4 will be connected for rotation in an opposite direction to shift the bearing 7 so that the web will again be shifted toward the right.

To prevent the connection of the field windings 67 and 80 in parallel, the armatures 72 and 82 of the directional contactors 9 and 8, respectively, are interlocked by the interlocking bar 87, so that neither the contact members 64 nor the contact members 79 can be in circuit closing position at the same time. During normal operation the contact members 55, 56, 61 and 74 prevent the simultaneous energization of both directional contactors.

From the foregoing discussion it should be clear that regardless of the direction in which the web may be meandering at the instant it is in the mid-position or the desired path of travel, if a failure takes place at the left as assumed, the cycle of operation just explained is not changed by reason of the direction of meandering at the instant of failure.

If the failure takes place when the web 6 is at the left and in such a position that normally

the light falling on the phototube 14 would be intercepted, no change will, of course, take place in the position of the control relay 24, since this control relay will already be in its deenergized position by reason of the interception of the light at the left and the movement of the bearing 7 will of course be in such a direction that the web is shifted toward the right.

The only other remaining position of the web during a failure is at the right intercepting the light falling on the photo-tube 15 when some failure takes place at the left. If the web be at the right, the actuating coil 23 will, of course have energized the motor 4 to operate in such a direction as to shift the web toward the left. The instant the failure takes place at the left contact members 56 will be opened, and in consequence, the circuit for the magnetizing coil 78 will be open. It would thus seem, without an exact knowledge of the operation of the control devices, that the motor 4 would reverse its operation to shift the web toward the right even though the web 6 is already at the right. Such is, however, not the case if the web is at the right, actuating coil 23 is deenergized and any failure at the left deenergizes coil 22. The closure of the contact members 55 therefore cannot establish a circuit for the magnetizing coil 62 since the contact members 61 are open.

The web 6 being at the right, contact members 13 will be closed, and in consequence contact members 76 will be closed. Furthermore, contact members 60 will be closed and at the instant of any failure at the left, contact members 54 are closed with the result that the actuating coil 86 of the contactor 26 is energized and contact members 59 close. Since both sets of contact members 59 and 76 are closed, a circuit is established for the magnetizing coil 62. However, since the directional contactor 8 is still closed, has an inductive time constant, and is interlocked with the directional contactor 9 the motor 4 will continue to shift the web toward the left and such shifting will continue for an interval of time sufficiently long so that the web will be shifted to no longer intercept the light falling on the photocell 15, whereupon the circuit for the actuating coil 86 is opened. The energization of the magnetizing coil 62 is thus not continued through the contact members 59 and 76, because the reenergization of the actuating coil 23 opens the contact members 73 with the result that contact members 58 are closed, and closes contact members 61. The energization of the magnetizing coil 62 thus continues through the contact members 55 and 61. The web is thus shifted toward the right and when again intercepting light falling on the photocell 15, contact members 60 are closed and the directional contactor 8 is energized through the contact members 59 and 58. The direction of travel of the web 6 will thus be controlled by the cooperative action of the photocell and source of light and the portion of the system of control disposed at the right edge of the tube.

The master relay 27 and the cooperative action of the other control elements has hereinbefore been described in considerable detail, assuming a failure of a light, a photocell or an electric discharge device, or any two or all of these devices at the left. If such failure takes place at the right, since the system of control is entirely symmetrical, the controlling action will be exactly as hereinbefore discussed except that the web will be maintained in the desired path of travel with the coaction of the left edge of the web with

the photocell and the source of light and the portion of the system of control controlled by these units disposed at the left. It should be apparent from the foregoing explanations that regardless of the position of the web 6 and regardless of the side at which a failure takes place the web nevertheless will be maintained within its desired path of travel.

To apprise the attendant of the fact that a failure has taken place at one or the other side of the web, the contactor 26 is provided with the contact member 77 which, when closed by the simultaneous deenergization of the coils 22 and 23, energizes the light 90, which may be a red light.

The closing of the contact member 77 also energizes the actuating coil 91 of the time limit device 48. As long as no failure of at least a pair of units takes place one of the units being disposed on one side of the web and the other at the other side of the web, the contact member 77 will be closed intermittently and in consequence the energization of the coil 91 will be interrupted from time to time with the result that the contact members 47 will remain closed by reason of the delay effected by dash pot 102. If, however, certain units fail at both the right edge and the left edge of the web, or if the power fails on the buses 16 and 17, the contact members 54 and 60 will remain closed indefinitely with the result that the time limit device 48 will open its contact members 47, thus deenergizing the actuating coil 49 of the line contactor 50, which thereupon opens the contact member 51. The opening of the contact member 51 deenergizes the motor 4 whereas the opening of certain contact members in controller C opens a circuit in the system of control for the main motor M of the machine to stop the entire machine.

In the modification shown in Fig. 2, the same elements shown in Fig. 1 are designated with the same reference characters found in Fig. 1 and elements shown in Fig. 2 that are similar to elements shown in Fig. 1, are provided with similar reference characters. However, the modification shown in Fig. 2 operates somewhat differently than the embodiment shown in Fig. 1. For instance, if the web 6 be in the position shown and meander toward the left to intercept the light falling on photocell 14 actuating coil 22 is deenergized and in consequence contact members 55 close, establishing a circuit for the actuating coil 162 of the directional contactor 169 through the contact member 61 of the control relay 25. Operation of the directional contactor 169 closes the contact members 164 thus energizing the motor 4 to shift the web toward the right.

If one operation of the motor 4 were to accomplish an insufficient movement of the web 6 toward the right, the cycle will be repeated until the web 6 does in fact move toward the right to intercept the light falling on photocell 15. When the light falling on photocell 15 is intercepted, the actuating coil 178 of the directional contactor 169 is energized and contact members 179 are closed. The motor 4 is thus operated to shift the web 6 toward the left.

If any one of the units, the light 13, the photocell 15, or the electric discharge device 21 at the right fails, the actuating coil 23 will be deenergized and the web will be shifted toward the left until the light falling on photocell 14 is intercepted, whereupon contact members 188 are

closed. The closing of contact members 158 cannot at this time establish an energizing circuit, since the contact members 59' of the contactor 26' are still open. Furthermore, when the 5 actuating coil 22 is deenergized, the energizing circuit for the actuating coil 178 is broken at the contact members 56. Furthermore, the failure at the right caused the closing of the contact members 160 and somewhat later caused the 10 closing of contact members 176. As has just been suggested the contact members 160 and 176 are so positioned on the armature of the control relay 24 that the contact members 160 close before the contact members 176 close. Similarly 15 the contact members 154 and 158 on the control relay 24 are so positioned that the contact members 154 close considerably earlier than contact members 158.

It should be noted that the distance between 20 the elongated contact fingers adjacent the contact members 154 and 160 is much less than the distance between the contact fingers adjacent contact members 158 and 176, respectively.

If there be a failure at the right and the web 25 has been moved to the left sufficiently to intercept the light passing to photo-cell 14, contact members 154 and 59' close before contact members 158 close. Coil 162 is thus energized ahead of the energization of coil 178.

30 When the failure is at the left, the web is, of course, shifted toward the right and when intercepting the light passing to the photo-cell 15 the coil 23 is deenergized. The contact members 160 and 59' close before contact members 176 35 close, with the result that coil 178 is energized ahead of coil 162. The mechanical interlock 187 further aids in preventing the possibility of improper operation.

By reason of the failure at the right, contact 40 members 160 and 176 are closed and when the web intercepts the light falling on the photocell 14, contact members 154 close considerably ahead of the closing of contact members 158 and thus cause the operation of the contactor 26' to close 45 the contact members 59', thereby establishing a circuit for the actuating coil 162 of the directional contactor 109 through the contact members 59' and 176. Once the directional contactor 109 has operated, the mechanical interlock 187 prevents the operation of the directional contactor 108. It is therefore clear that 50 the deenergization of the actuating coil 22 by reason of the interception of the light falling on the photocell 14 by the web 6 causing the closing 55 of the contact members 158 will not cause the closing of the contact members 178 even though the contactor 26' is energized and its contact members 59' are closed. The web will therefore be shifted toward the right until the actuating 60 coil 22 is again energized whereupon actuating coil 162 will be deenergized, since the circuit for the contactor 26' is open at the contact members 154 and an energizing circuit is established for the directional contactor 108 through the contact members 56 and 14. The cycle of operation 65 will be very similar if a failure should take place at the left. In this modification, it is also entirely immaterial whether the web be at the side where the failure takes place and also immaterial whether the web be meandering in one 70 or the other direction, or whether it be in its desired path of travel or at the side where no failure takes place. The control is nevertheless such that the web is maintained in the desired path of travel.

In the modification shown in Fig. 2, the proper sequence of operation and cooperative action of the control relays with the contactor 26' was secured through a proper positioning of the contact members. A similar result can, however, 5 be obtained by the use of suitable time limit relays. This use of time limit relays is shown in Fig. 3. The normal operation for the modification shown in Fig. 3 is in every respect similar to the normal operation for the modifications shown 10 in Figs. 1 and 2. However, if a failure takes place of any one of the units, light, photocell, or electric discharge device, at one or the other side of the web the cooperative action of the contactor 226 coacting with the time limit relays 93 15 and 94 and the control relays 24 and 25 rearranges the circuits so that the control is shifted to the side where no failure has taken place.

The time limit relays 93 and 94 are very similar to the time limit directional contactors 8 and 9 shown in Fig. 1, and have a pair of magnetizing coils 278 and 262 and a pair of neutralizing coils 281 and 269 connected in series circuit relation with a resistor 270. If a failure takes place at the left, contact members 55 and 61 are 20 closed, establishing an energizing circuit for the actuating coil 162 of the directional contactor 109 thereby closing the contact members 164 whereupon the motor 4 is operated to shift the web toward the right. Since a failure was assumed to have taken place at the left, contact members 153 are closed shunting the magnetizing coil 262, whereupon the contact members 258 are closed after a definite interval of time. If the web is moved an amount sufficient to intercept the light at the photocell 15, contact members 260 close whereupon contact members 159 close thus establishing a circuit from a bus 10 through contact members 159 and 258 to the actuating coil 178 of the directional contactor 108, with the result that the contact members 178 are closed. The web will thus be shifted toward the left and the time during which such shifting will take place is determined by the time limit relay 94 which will, of course, close its 30 contact members 276 when the contact members 173 are closed by the interception of the light falling on the photocell 15. The time constant is chosen of sufficient length that the web is shifted toward the left by an amount sufficient 35 that the light will again fall on the photocell 15, and the magnetizing coil 278 is reenergized to open the contact members 276. However, since contact members 55 and 61 are closed, the web will be shifted toward the right nevertheless.

The modification shown in Fig. 4 shows a mechanical scheme for rearranging the circuit connections so that the control may be shifted to one or the other side in case of failure of certain elements of a group of elements at one 40 or the other side of the web. The control relays 24 and 25 are provided with dogs 95 and 96 for operating the switches 92. This operation being effected by the coaction of the dogs 95 and 96 with the ends 97 and 98, respectively, of the bar 99. The switches 92 are held in the full line position shown by the spring 100. If a failure should have taken place at the left, the bar 99 will be held in the dotted line position with the result that the contact members 358 are closed. 45 A failure of any unit at the left will, of course, close contact members 55 and since the contact members 61 are closed, the directional contactor 109 will be actuated by the energization of coil 162. Operation of the directional contactor 109 50

closes the contact members 164 with the result that the motor 4 is energized to shift the web toward the right.

As soon as the web has been shifted toward the right an amount sufficient to intercept the light falling on the photocell 15, contact members 60 are closed thus energizing the coil 286 of the contactor 226 and thus closing the contact members 159. A circuit is therefore established from the bus 10 through the contact members 159 and 358 through the conductor 277, and actuating coil 178 of the directional contactor 108. Contact members 179 are thus closed and motor 4 is energized to shift the web toward the left. When the light is no longer intercepted at the right, the contact members 60 open, and directional contactor 108 is thus deenergized and contact members 61 closed thereby energizing the directional contactor 109. The web is thus maintained in its desired path of travel despite the fact that a failure of one unit has taken place at one edge of the web.

My system of control as hereinbefore explained thus controls the transverse movement of the web by indiscriminately calling for web movement control upon the control means at the sides of the web for one operating condition of the entire control system and by indiscriminately calling for web movement upon the control means at the sides of the web for another condition of the entire control system.

Viewed differently, my invention provides for a movement, of a given line longitudinally of the web, away from the outer limits of the desired path of travel of the web for one arrangement of the control and provides for a positive oscillatory movement, of the given line longitudinally of the web, within the outer limits of the desired path of travel of the web for another arrangement of the control, and wherein such different arrangements are automatically effected upon the failure of a certain element or elements, or units, in a group of a plurality of groups of units in the entire system of control.

1. I am fully aware of the fact that other circuit arrangements and other mechanical schemes than the particular structures and arrangements hereinbefore disclosed may be devised by those skilled in the art to accomplish the novel results of my invention, particularly after those skilled in the art have had the benefit of the teachings embodied in the foregoing specification. However, I wish to be limited only by the appended claims and the pertinent prior art.

2. I claim as my invention:

1. In a system of control, having a plurality of elements, for a machine moving a web of material longitudinally of itself and wherein the web is subject to move out of a desired path of travel, in combination, control circuits having a plurality of arrangements, means for moving the web so that a given line longitudinally of the web is moved away from the outer limits of the desired path of travel of the web for one arrangement of the control circuits, and means for positively oscillating the web, so that the given line longitudinally of the web moves within the outer limits of the desired path of travel for another arrangement of the control circuits, said control circuits including means for automatically changing from one arrangement of the control circuits to another arrangement of the control circuits by the failure of certain elements in the system of control.

2. In a control system for a machine operating

on webs of material that are subject to meander unlimitedly from a desired path of travel, in combination, a plurality of rolls for supporting and causing a web of material to travel in a given direction, photo-electric means disposed adjacent the edges of the web, lights disposed to normally act on said photo-electric means but which cease to act on said photo-electric means when the web meanders to a position to intercept the light falling on said means, and roller-axis-shifting means responsive to a certain operation of said photo-electric means when the light is intercepted at either side for causing the axis of one of said rolls to be disposed at an angle to the axes of the other rolls to thus shift the web away from the side at which the light is intercepted, and means responsive to a failure of either the light or the photo-electric means, or both, adapted to alter the control system so that said roller-axis-shifting means, in response to the portion of the photo-electric means not affected by the mentioned failures, will cause the axis of one of said rolls to be shifted back and forth to change its angle with reference to the axes of the other rolls to thus shift the web back and forth within the desired path of travel.

3. In a system of control for a machine driving a web in a given general direction and wherein the web, in the absence of travel control means, moves transversely that is, meanders indiscriminately towards either side and out of the limits of a desired path of travel for the web, in combination, electric control means at the sides of the web adapted to be thus indiscriminately influenced in operation by transverse movements of the web for one operating condition of the system of control, and by reason of restrained meandering of the web to be indiscriminately influenced in operation by the transverse movements of the web for another operating condition of the system of control, motor means adapted to control the transverse movements of the web, control circuits set up for said motor means by the electric control means when subject to indiscriminate influence by the web to cause said motor means to operate to prevent a certain line longitudinally of the web from moving beyond the outer limits of travel of the web, and control circuits set up for said motor means by the electric control means when subject to discriminate influence by the web to cause said motor means to operate to positively move the web to and fro so that said given line longitudinally of the web is maintained within the desired path of travel.

4. In a system of control for a machine driving a web in a given general direction and wherein the web, in the absence of restraining means, moves transversely, that is, meanders indiscriminately to either side and out of the limits of a desired path of travel for the web, in combination, electric control means at the sides of the web adapted to be indiscriminately influenced in operation by transverse movements of the web for one condition of the system of control and by reason of restrained meandering of the web to be indiscriminately influenced in operation by the transverse movements of the web for another condition of the system of control and motor means, controlled by said electric control means, adapted to control the transverse movements of the web.

5. In a control system for a machine operating on a web of material and moving said web in a given general direction, said web having the habit

- of moving laterally to thus depart from a desired path of travel of the web, in combination with, control means, responsive to a certain lateral movement of the web, disposed at each side of 5 the web and adapted to reposition the web to the desired path of travel, said control means including means responsive to certain conditions of operation for restricting the controlling action to the control means at one side of the web.
- 10 6. In a control system for a machine operating on a web of material and moving said web in a certain general direction, in combination, electric control means having a plurality of units disposed at each edge of the material, and control means 15 subjected to the control of said electric control means and adapted to keep the web of material in a given path, said control means including means responsive to a failure of one unit of the electric control means at one edge regardless of 20 which edge to make the control means subject to the electric control means none of whose units have failed, whereby the web of material is maintained in the desired path of travel despite the said failure of one unit.
- 25 7. In a control system for a machine operating on web material, photo-electric means disposed adjacent each side of the material, and control circuits and web-shifting means subject to the control of said photo-electric means for maintaining the edges of the material away from said photo-electric means, said control circuits including means responsive to a partial failure of the control system adapted to modify the operation of said photo-electric means and alter the arrangement of the control circuits so that the web-shifting means operates to maintain one edge of the web of material adjacent to one of said photo-electric means.
- 30 8. In a control system for a machine operating on web material and having a plurality of elements including electric control means disposed adjacent each edge of the material, control devices, controlled by the electric control means, adapted to maintain the edges of the material away from the electric control means, said control devices including means, responsive to certain changes in operating characteristics of said electric control means, adapted to control the transverse movement of the web of material so 35 that one edge thereof is maintained adjacent one of said electric control means.
- 35 9. In a system of control for a machine moving a strand of material longitudinally of itself and wherein the strand has the habit of meandering out of a desired path of travel, in combination, two groups of control devices, coacting with the strand and with each other, adapted to restrict lateral meandering movement of the strand to a certain path of travel when all the devices of both 40 groups are in operative condition and adapted to restrict the coaction of the strand to one group of devices when either any one, several or all the devices of the other group fail, to thus nevertheless restrict the movement of the strand within 45 the desired path of travel.
- 40 10. In a system of control for a machine for moving a strand of material longitudinally of itself and wherein the strand has the habit of meandering out of a desired path of travel, in combination; two control means, each including, among other elements, a photo-cell, an electronic tube, and a light so disposed that the photo-cell may be subjected to the radiant energy emitted by the light, coacting with the strand and with 45 each other so as to restrict the lateral meander-
- ing movement of the strand to a certain path of travel when all the elements of both of the two control means are in operative condition and adapted to restrict the coaction of the strand and the two control means to one control means when either any one, several, or all the elements, comprising the light, photo-cell, and electronic tube, of one group fail.
- 50 11. In a web-regulating device for a machine wherein a traveling web is subject to deviations from a given or normal path of travel, in combination, web-actuating means for causing a normal movement of the web in the direction of its length, electronic means responsive to a predetermined deviation of the web in a given direction transversely of its normal movement to cause shifting of the web back to its normal movement, electronic means responsive to a deviation of the web from its normal path of movement greater than said predetermined deviation for stopping the operation of both the web-actuating means and the electronic means, and control means, comprising part of said electronic means, adapted, upon a failure of any one or several of certain elements of said electronic means to cause the web to be shifted back and forth within the range of the normal movement.
- 55 12. In a control system for a machine operating on a web of material to move the web in a certain direction longitudinally of itself and in which machine the web has the habit of effecting meandering transverse shifts, in combination, web shifting means adapted to cause the web to shift to and fro transversely of the general direction of motion of the web by a small amount, electronic means, responsive to a predetermined transverse meandering shift of the web, adapted to control said web shifting means to effect a compensative transverse shift of the web in a direction opposite to the meandering transverse shift, and further electronic means and means, responsive to a failure of part of said electronic means, coacting to control said web shifting means to operate so as to positively shift the web transversely of its movement over a small substantially fixed range.
- 60 13. In a control system for a machine operating on a web of material to move the web longitudinally of itself in a given direction and in which machine the web has the habit of meandering transverse shifts, in combination, web shifting means adapted to cause the web to positively shift transversely of its general direction of motion, electronic means, responsive to a predetermined meandering shift of the web, adapted to control said web shifting means to positively shift the web in a transverse direction opposite to said transverse meandering shift, further electronic means including control means responsive to the failure of a part or all of either of said electronic means to cause the particular electronic means, no parts of which have failed, to alone assume the control of said web shifting means, responsive to the electronic means no parts of which have failed, to so control the web shifting means to positively shift the web to and fro over a substantially predetermined range.
- 65 14. In a control system for a machine operating on a web of material to move the web in a given direction longitudinally of itself and in which machine the web has the habit of meandering from side to side, in combination, web shifting means adapted to cause the web to shift transversely of the general direction of motion

of the web, and electronic means disposed just beyond the edges of the web, responsive to a pre-determined transverse meandering shift of said web, adapted to control the said web shifting 5 means to positively shift the web away from the particular electronic means towards which the meandering shift took place, and control means responsive to the failure of a part or all of the electronic means at either edge of the web to 10 cause the web shifting means to positively shift the web to and fro over a small distance so that the meandering transverse shifts of the web above a predetermined magnitude are prevented.

15. In a system of control for a machine driving a web in a given general direction and wherein the web, in the absence of travel control means, moves transversely, that is, meanders indiscriminately towards either side and out of the limits of a desired path of travel for the web, in 20 combination, photo-electric scanning means at each side of the web adapted to be thus indiscriminately influenced in operation by meandering transverse movements of the web for one operating condition of the system of control, and 25 by reason of restrained meandering of the web to be indiscriminately influenced in operation by the transverse movements of the web for another operating condition of the system of control, motor means adapted to control the transverse 30 movements of the web, control circuits set up for said motor means by the photo-electric scanning means when subject to indiscriminate influence by the web to cause said motor means to operate to prevent a certain line longitudinally of the web from moving beyond the outer 35 limits of travel of the web, and control circuits set up for said motor means by the photo-electric scanning means when subject to discrimi-

nate influence by the web to cause said motor means to operate to positively move the web to and fro so that said given line longitudinally of the web is maintained within the desired path of travel.

5

16. In a control system for a machine operating on a web of material and moving said web in a given general direction, said web having the habit of haphazardly moving laterally to thus depart from a desired path of travel of the web, 10 in combination, with photo-electric control means, responsive to a certain lateral movement of the web and disposed at each side of the web beyond the edges and thus out of contact with the web, adapted to effect repositioning of the 15 web to the desired path of travel, said control means including means responsive to certain operating conditions of the system of control, adapted to restrict the controlling action to the photo-electric control means at one side of the 20 web.

15

17. In a control system for a machine operating on web material and having a plurality of elements including photo-electric control means disposed adjacent but just beyond each edge of 25 the material, control devices, controlled by the photo-electric control means, adapted to maintain the edges of the material away from the photo-electric control means, said control devices including means, responsive to certain 30 changes in operating characteristics of either one of said photo-electric control means, adapted to control the transverse movement of the web of material so that one edge thereof is maintained adjacent one of said photo-electric control means.
